Primary Examiner — Susan Moon Lee(74) *Attorney, Agent, or Firm* — Standley Law Group LLP(57) **CLAIM**

The ornamental design for a bird feeder, as shown and described.

DESCRIPTION

FIG. 1 is a front perspective view of an embodiment of the bird feeder;

FIG. 2 is a rear elevation view of the FIG. 1 embodiment; FIG. 3 is a right side elevation view of the FIG. 1 embodiment, the left side elevation view being a mirror image thereof; FIG. 4 is a top plan view of the FIG. 1 embodiment;

FIG. 5 is a bottom plan view of the FIG. 1 embodiment.

FIG. 6 is a front perspective view of the base used in the embodiment of the bird feeder in FIG. 1;

FIG. 7 is a right side elevation view of the FIG. 6 base, the left side elevation view being a mirror image thereof;

FIG. 8 is a top plan view of the FIG. 6 base; and,

FIG. 9 is a bottom plan view of the FIG. 6 base.

Broken lines and unshaded portions contained within broken lines are not claimed.
